UNITED STATES PATENT OFFICE.

CHRISTIAN SEYBOLD AND HANS DEHM, OF DÜREN, GERMANY.

ROTARY KNOTTER WITH DEEPLY-IMMERSED SCREENING-DRUM FOR PAPER-MAKING.

1,153,579.

Specification of Letters Patent. Patented Sept. 14, 1915.

Application filed July 8, 1913. Serial No. 777,814.

To all whom it may concern:

Be it known that we, CHRISTIAN SEYBOLD and HANS DEHM, citizens of the German Empire, residing at Düren, Germany, have invented new and useful Improvements in 5 Rotary Knotters with Deeply-Immersed Screening-Drums for Paper-Making, of which the following is a specification.

The present invention relates to a rotary 10 knitter with deeply immersed screening drum for paper making, in which either the trough or the screening drum is oscillated, so as to force the pulp through the meshes of the screening drum.

15 The object of the present invention is to vary the oscillation curve of the oscillating part in such a manner, that the oscillations can be adapted to the consistency of the pulp to be dealt with. This is essentially 20 obtained by the oscillating part (trough or screening drum) being supported on one side on pendulum supports, and on the other side on resilient supports, and being driven from the top end of a vertical connecting 25 rod, the lower end of which is coupled to the driving eccentric and the shaft of which oscillates in an adjustable bearing. By displacing this bearing relatively to the driving eccentric the fulcrum of the connecting 30 rod is displaced and thereby the curve of oscillation of the oscillating part is varied. In consequence thereof the latter will oscillate with a different stroke according to the 35 position of the bearing and a rotary knitter is obtained the shaking of which is at the same time elastic and variable within wide limits.

In the accompanying drawing the new 40 knitter is exemplified in Figure 1 which is a cross section. Fig. 2 is a longitudinal section through the device for adjusting the curve of oscillation.

With the constructional form shown it has 45 been assumed, that the trough oscillates. But just as well also the trough may be stationary and the screening drum may oscillate. At one end the trough rests on pendulum supports *b* and at the other side on spring supports *c*. Both the pendulum 50 supports *b* and the spring supports *c* are fitted to a common bed-plate *d*. The trough is driven from the top end *e* of a vertical connecting rod *f* the lower end *f* of which is connected to the driving eccentric *h*. The 55 shaft of the connecting rod *f* oscillates in a vertically adjustable bearing *i*. By this

means the trough *a* will, on the driving shaft *h* revolving, perform closed, approximately elliptic oscillations, so that the pulp is driven through the meshes of the screening drum. The great weight of the oscillating part, filled with pulp and water is received on the drive side by the resilient supports *c*, so that eccentric *h* and connecting rod *f* are relieved.

For varying the curve of oscillation of the oscillating part *a*, and adapting the oscillations of the same to the consistency of the pulp, the connecting rod bearing *i* is vertically displaced relatively to the driving eccentric *h*. For this purpose the following arrangement is provided: The connecting rod bearing *i* is fitted with a ball and socket joint and the ball *l* encircling the shaft of the connecting rod engages with a ledge *m* 75 in a longitudinal groove *n* of the said shaft. Hereby the ball is non-rotatably secured to the connecting rod, but can be longitudinally displaced on the shaft of the same. The ball is carried in a bearing *i*. This bearing is 80 screwed with a male thread in an upright rotatable threaded sleeve *o*, which engages by means of an annular ledge *p* in an annular groove *g* in a casing *r* fitted to the bed plate. By turning the threaded sleeve *o* by 85 means of a handwheel *s* provided at its upper end the bearing *i* can be screwed up or down. By the fulcrum of the connecting rod being thus displaced relatively to the eccentric, the curve of oscillation of the oscillating part is varied, so that the latter will oscillate with a different stroke according to the position of the bearing.

We claim:

1. In a rotary knitter of the class described, in combination, a screening drum, a trough, one of said members being capable of oscillating in a closed curve, pendulum supports supporting said oscillating member at one side thereof, spring supports supporting said oscillating member at the other side thereof, a shaft provided with an eccentric, a connecting rod operatively connected to said eccentric and to said oscillating member, and an adjustable bearing 100 for said connecting rod positioned between the ends thereof, whereby the curve of oscillation of said oscillating member may be varied.
2. In a rotary knitter of the class described, in combination, a screening drum, a trough, one of said members being capable 110

of oscillating in a closed curve, pendulum supports supporting said oscillating member at one side thereof, spring supports supporting said oscillating member at the other side thereof, a shaft provided with an eccentric, a connecting rod operatively connected to said eccentric and to said oscillating member, a threaded sleeve surrounding said connecting rod, a threaded bearing fitting in said sleeve and adjustable with respect thereto, and a bearing ball within said bearing and encircling said connecting

rod, said ball being movable in the direction of the length of said rod and being held from rotating with respect thereto.

In testimony whereof we have signed our names to this specification in the presence of two subscribing witnesses.

CHRISTIAN SEYBOLD.
HANS DEHM.
